UNITED STATES PATENT OFFICE.

PERCY HARRISON, OF BALTIMORE, MARYLAND, ASSIGNOR TO HARRISON MANUFACTURING COMPANY, OF BALTIMORE, MARYLAND, A CORPORATION OF MARYLAND.

COLLAR ATTACHMENT.

1,082,517.

Specification of Letters Patent.

Patented Dec. 30, 1913.

Application filed March 11, 1912. Serial No. 683,014.

To all whom it may concern:

Be it known that I, PERCY HARRISON, a citizen of the United States, residing at Baltimore, in the State of Maryland, have 5 invented a new and useful Collar Attachment; and I do hereby declare the following to be a full, clear, and exact description of the invention, such as will enable others skilled in the art to which it appertains to 10 make and use the same.

This invention relates to an attachment for collars, the object of which is to prevent the neck-tie from binding, when adjusting the same.

15 Another object of the invention is the provision of an attachment of this nature, in which novel features of construction exist.

One of the features of the invention is the 20 production of means to prevent the attachment from slipping.

The invention comprises further features and combination of parts, as hereinafter set forth, shown in the drawings and claimed.

25 In the drawings:—Figure 1 is a view in perspective, showing the application of the attachment to a collar, the attachment being shown in dotted lines. Fig. 2 is a view of the attachment removed from the collar. Fig. 3 is a sectional view on line 3—3 of Fig. 1. Fig. 4 is a cross sectional view of the collar attachment.

Referring to the drawings 1 designates the collar, which is of the usual construction, 35 while 2 denotes the attachment, which may be made of sheet steel or aluminum or any other suitable material.

The attachment comprises an elongated sheet metal material bent longitudinally 40 upon itself as at 2^a, forming the two sides 3 and 4, and then again as at 5 to form the elongated flange 6, which is disposed between the two sides 3 and 4. The bend 5 is more in the form of a curve, as shown, 45 so as to hold the sides 3 and 4 considerably spaced apart, in order that the neck-tie may easily slide between the two sides 3 and 4 of the attachment.

The outer faces of the sides 3 and 4 are 50 provided with pointed lugs 7, adapted to slightly pierce the collar, in order to prevent the attachment from slipping downwardly. In cases where the pointed lugs do not properly act to prevent the slipping 55 of the attachment, which especially occurs

when the two portions 8 and 9 of the collar do not come together sufficiently to permit the lugs to pierce them, the attachment is provided with an extension plate 10 having a recess 11, in which the collar button 12 60 engages, thereby properly supporting the attachment.

In applying the attachment, the two sides 3 and 4 thereof are partly spread apart, in order to permit the insertion of the necktie. The necktie is arranged between the flange 6 and the side 4, and being that the bend 5 is in the form of a curve or roll, the necktie will easily slip, in order that the same may be properly adjusted. 65

In manufacturing this collar attachment, some may be made with the extension 10, and others without the extension.

The invention having been set forth, what is claimed as new and useful is:— 70

1. An improved scarf-holding and spacing device for collars comprising an elongated plate bent longitudinally upon itself to form two sides, one of which is curved longitudinally upon itself and terminating 80 in an elongated flange disposed between the two sides, the flange constituting means adapted for supporting a necktie between it and one of the sides, and also for holding the sides of the device separated, the outer 85 faces of the sides having pointed lugs adapted to engage the collar to support the spacing device.

2. An improved scarf-holding and spacing device for collars comprising an elongated plate bent longitudinally upon itself to form two sides, one of which is curved longitudinally upon itself and terminating 90 in an elongated flange disposed between the two sides, the flange constituting means 95 adapted for supporting a necktie between it and one of the sides and also for holding the sides of the device separated, the outer faces of the sides having pointed lugs adapted to engage the collar to support the spacing device, the side having the flange being provided with a substantially centrally located extension having a recess adapted to 100 engage the collar-button.

3. An improved scarf-holding and spacing device for collars comprising an elongated plate bent longitudinally upon itself to form two sides, one of which is curved longitudinally upon itself and terminating 105 in an elongated flange disposed between the 110

two sides, the flange constituting means adapted for supporting a necktie between it and one of the sides and also for holding the sides of the device separated, the side 5. having the flange being provided with a substantially centrally located extension having a recess adapted to engage the collar-button.

4. An improved scarf-holding and spacing device for collars comprising an elongated piece of thin flexible material bent longitudinally upon itself to form two sides, having a space therebetween sufficient to receive a necktie, one of which is curved lon-

gitudinally upon itself and terminating in 15 an elongated flange disposed between the two sides, the flange constituting means adapted for supporting a necktie between it and one of the sides, and also for holding the sides of the device spaced apart.

In testimony whereof I have signed my name to this specification in the presence of two subscribing witnesses:

PERCY HARRISON.
